UNITED STATES PATENT OFFICE

LARS M. THORSON AND KENNETH B. WARD, OF CHICAGO, ILLINOIS

COMBINATION WARM AIR CLEANER AND HEAT DEFLECTOR

Application filed September 19, 1927. Serial No. 220,577.

Our invention relates to a combination warm air cleaner and heat deflector, designed especially for use in connection with radiators and the like but capable of utilization 5 in connection with any device to which such a structure may be advantageously applied, and the invention has for its object the provision of an improved construction of the kind in which a moisture carrying device is 10 arranged across a warm air passageway.

Salient objects of our invention are: to provide means for cleaning the warm air; to provide means for increasing the humidity of the warm air; to provide means for 15 proving the prophylactic quality of the air; and to provide an arrangement by means of which the air carrying convected heat is deflected in approximately horizontal directions.

It is within the province of our present invention to provide a combination warm air cleaner and heat deflector of a simple, efficient and durable construction, which will be highly convenient in use, and one in which 25 the parts are so constructed and arranged that there will be no overflow or leakage of water from the device.

These and other objects are attained by the means herein described and illustrated 30 in the accompanying drawings, in which—

Fig. 1 is a perspective view of a preferred embodiment of our device;

Fig. 2 is a vertical central cross-sectional view of the device shown in Fig. 1;

Fig. 3 is a view similar to Fig. 2, but showing a modified form of the device; and

Fig. 4 is a top plan view of the upper reservoir shown in Fig. 3.

Although, for the purpose of illustrating 40 a practical application of our device, we have shown in Fig. 2 a selected embodiment thereof in association with a radiator, it is to be understood that in practice our device is not confined to such particular association, but 45 may be employed in cooperation with any suitable means capable of supplying warm air.

In the embodiment of our invention shown in Figs. 1 and 2, as a preferred example, 50 11 designates in general a box-like body or duct

structure which is provided with an inlet opening 12 at the bottom and with a series of outlet openings 13 in its front face or panel. This form of the device is designed to be mounted upon a radiator as 14, its bottom being adapted to rest thereon as shown, so that the warm air rising from the radiator will enter the body through the bottom opening 12. The stream of warm air rising 55 upwardly within the body 11 is ultimately deflected out through the series of front openings 13 in approximately horizontal directions, the arrows associated with Fig. 2 indicating the path of the air passing through the device.

Within the body 11 are arranged two reservoirs in the form of water holding pans 15 and 16 which may be referred to, respectively, as an upper pan and a lower pan; and from an inspection of Fig. 2 it will be noted in this connection that although situated at different levels or in different horizontal planes these pans are so related that the path for the rising stream of warm air leads therebetween and that water 17 falling from the 60 overflow lip or half-round outwardly and downwardly projecting edge 18 of the upper pan 15 will be caught by the lower pan 16. Water carrying means in the form of a sheet of porous wicking 19 is arranged to extend upwardly from the interior of the upper pan 15, to overlie the overflow lip 18 thereof, and then to proceed downwardly across the air passageway and into the interior of the lower pan 16. Warm air rising 65 within the body must pass through the downwardly extending portion or reach of the wicking before it can escape through the front openings 13. Instrumentalities as hooks 20, shown in connection with the upper pan 15, or weights 21, shown in connection with the lower pan 16, may be employed as means for holding the wicking in position. As shown in the drawings, the end portions of the wicking 19 are maintained 70 under water within the pans 15 and 16. The wicking sheet 19 may consist of any suitable material readily pervious to air and capable of raising water by capillary action.

After being raised to the crest of the wicking 75 130

upon the edge 18 by capillary action, the moisture is influenced by force of gravity to move toward the lower pan. By providing at the upper pan a short reach where 5 water is raised by capillary action, and by providing a long reach where the water is influenced by gravity, the distributive capacity of the wicking for uniformly and adequately humidifying the warm air is greatly 10 increased. The top or cover 23 is removable to facilitate filling the pans with water and to permit the removal of the wicking for laundering when required; and the pans are preferably removable in order that they 15 may be readily cleaned. Brackets 22 provide supporting means for the upper pan 15.

Referring to Fig. 3, where we show a modified form of our device, 11a designates in general the box-like body or duct structure which is made with a bottom inlet opening 12a and front outlet openings 13a. In this embodiment, as in the other, there are two water pans located at different levels, but the upper pan is of U-shaped formation, the same having two sections or arms 15a and 15b spaced apart and connected at one end as shown in plan in Fig. 4. The lower water pan 16a, located directly below the open space 25 between the sections 15a and 15b, spans the bottom of the opening 12a and divides the lower interior of the body into two air passages. 30

In this form of construction, a wicking 35 19a has portions thereof maintained under water within the sections 15a and 15b of the upper pan and also within the lower pan 16a. Said wicking is mounted by passing it about a retaining rod 21a within the lower pan 40 16a and by extending its two resulting reaches or runs upwardly in opposed relation as shown. In the present exemplification, both of the reaches are shown as terminating within section 15a, one of them before entering therein, being trained over the 45 half-round edge 18a, while the other of the reaches before entering therein, is taken over the half-round edge 18b, is secured by a retaining rod 25b within the section 15b, and 50 finally is extended across both of the edges 18b and 18a to intersect the space or air passage therebetween. The extremities of the wicking may be held in place within section 15a by hooks 20a or any suitable means. 55 If desired, the wicking may for convenience in handling consist of two or more sheets instead of a single sheet. It will be evident that by means of the arrangement shown in Fig. 3, the rising warm air is required to 60 pass through two stretches or reaches of the wicking, thereby greatly increasing the efficiency of the device. Any water draining from the wicking, dripping therefrom, or overflowing the edges 18a and 18b will fall 65 into the water pan 16a, which may have a ca-

pacity in excess of that of the combined sections 15a and 15b. If the water pan 16a be made with ample space to take care of substantially all the water in the upper sections, there can be no overflow or leakage from 70 the device when the atmosphere is highly humid, or when the heat fails in the radiator or is shut off, while the upper reservoir or waterpan 15a is filled to overflowing.

The device is preferably constructed of 75 sheet metal except as herein otherwise specified, but may be made of any other materials possessing the requisite structural and physical properties. The device is preferably made of ornate design to harmonize with 80 various kinds and types of furniture.

The device is prepared for use as follows: The upper pan is filled with water, while into the lower pan is introduced merely enough water to immerse a portion of the wicking 85 therein. When filling the upper pan, great care need not be exercised because after the pan has been filled, any excess water will pass over the overflow lip and will be caught in the lower pan. The overflow lip projects outwardly and downwardly from the upper edge of the wall of the upper pan and effectively prevents excess water from following down the outside of the pan and leaking. Immediately after the upper pan has been filled, 90 the level of the water will be above the elevation of the lower edge of the drip lip. After the device has been in operation for some time, more or less of the water in the upper pan will have been evaporated or consumed 100 consequently lowering the water level. It is thus clear that the water level in the upper pan is sometimes above but usually below the elevation of the lower edge of the drip lip or overflow lip 18, or 18a. In case the humidity is high no water need be put into the lower pan; and the amount of evaporation from the upper pan can be decreased by only partly filling it with water when a lower 105 humidity is desirable.

The device operates as follows: Warm air from any source enters the body through the bottom inlet opening, rises upwardly therein, passes through the intersecting wicking, and is discharged through the outlet openings in approximately horizontal directions. The overflow lip holds the sheet of wicking away from the adjacent side of the upper pan. This arrangement of the wicking with reference to the upper pan automatically increases the effective area of the wicking, which condition contributes substantially to the efficiency of the device. As previously intimated, the short or low lift at the upper pan greatly facilitates the moistening of the wicking since after the water is raised over the half-round edge, it will be influenced by gravity to move towards the lower pan with the result that the wicking is kept amply and uniformly moistened. By passing through 110 115 120 125 130

the moistened sheet of wicking, the warm air is automatically cleaned and humidified. The sheet of wicking can easily be replaced whenever it requires cleaning.

5 While we have shown and described certain selected forms of our invention, it is to be understood that these are capable of many modifications. Changes, therefore, in the construction and in the arrangements may be
10 made without departing from the spirit and scope of the invention as defined in the appended claims, in which it is our intention to claim all novelty inherent in our invention as broadly as possible in view of the prior
15 state of the art.

What we regard as new, claim, and desire to secure by Letters Patent is:

1. A device of the kind described comprising a body having an inlet opening and an
20 outlet opening and enclosing an air passageway extending between said openings; a water reservoir having two sections each of which is disposed on opposite sides of said passageway and each provided with an over-
25 flow lip; a drip pan located under said lips; and a moisture carrying fabric extending from the interior of one of said sections across said air passageway and into the interior of the other of said sections.

30 2. In combination, a casing having an inlet and an outlet and enclosing an air passageway extending between said openings; a water supply reservoir having two sections each of which is disposed on opposite sides of
35 said passageway; wicking extending from the interior of one of said sections across said passageway below the water level of said reservoir and into the interior of the other of said sections; and a drip pan located below
40 the wicking in said passageway.

3. In combination, a casing enclosing an air passageway extending between an inlet opening and an outlet arranged to discharge air in approximately horizontal directions; a
45 water supply reservoir having two sections each of which is disposed on opposite sides of said passageway; moisture carrying fabric extending from the interior of one of said sections across said air passageway above the
50 level of water in said reservoir and into the interior of the other of said sections.

4. In combination, a casing having an inlet opening through the bottom arranged to cover a radiator and an outlet opening arranged to discharge air in approximately horizontal directions; an air passageway enclosed by said casing and extending between said openings; a water supply reservoir in said passageway; and a sheet of porous moisture carrying fabric extending from the interior of said reservoir across said air passageway.
